UNITED STATES PATENT OFFICE.

LESLIE P. HIATT, OF PERU, IOWA.

WRENCH.

SPECIFICATION forming part of Letters Patent No. 233,507, dated October 19, 1880.

Application filed July 20, 1880. (Model.)

To all whom it may concern:

Be it known that I, LESLIE P. HIATT, of Peru, in the county of Madison and State of Iowa, have invented a new and Improved 5 Wrench, of which the following is a specification.

The object of this invention is to provide a wrench especially adapted to the unscrewing of bolts and nuts where but little room is given 10 for the movement of the wrench-handle.

Figure 1 is a plan of the wrench. Fig. 2 is a side elevation of the same, showing a portion in section on line *xx*, Fig. 1. Fig. 3 is a perspective detail view of the socket-plate.

15 Similar letters of reference indicate corresponding parts.

In the drawings, A represents the lever of the wrench, in whose enlarged circular end *a* is a vertical opening, *b*, in which the socket- 20 plate B revolves. Said plate B is provided

with notches in the periphery of its central portion, a socket, *B'*, and top and bottom annular flanges, *c d*, respectively, by means of which the plate is retained in the opening *b*,

25 the top flange, *c*, being retained in place by pins *f*, or other suitable device, and said top flange, *c*, is provided with a series of notches, *g*—in this instance with eight notches—deeply indented in its edge and at equal distances

30 apart, while the lever A has one deep recess, *h*, in the side of the opening *b*, directly beneath the nose of the pawl C, corresponding with the notches *g* of the flange *c*, and designed to receive the nose of said pawl C. The pawl

35 C is set centrally along the lever A of the wrench, its depending lug *k* being entered into a socket, *l*, in said lever A, and pivoted therein by the transverse pin *m*, while the uplifted rear end of said pawl C rests on a spiral

40 spring, D, that projects upward from the lever A, and thereby the nose *n* of said pawl C is held engaged in the recess *h* of the lever A and in a corresponding notch, *g*, of the socket-

plate flange *c*, while said nose *n* is disengaged at any time by pressure on the rear end of said 45 pawl C.

The plate B being set about a bolt or nut, and the recess *h* of the lever A being brought in correspondence with a notch, *g*, of said plate B, the nose *n* of the pawl C is entered into 50 said recess and notch *h g*, thereby connecting the lever A and plate B, so that they will move together, and when the lever A has been moved laterally as far as there is room for its movement, the pawl C is disengaged and the 55 lever A swung back as far as may be, so that its recess *h* shall come beneath another notch, *g*, when said pawl C is again engaged in both recess and notch *h g*, and in this manner the plate B and its inclosed bolt or nut may be 60 turned, the notches *g* in said plate B permitting short movements for engaging and disengaging the lever A.

The socket of the plate B may be made smaller to accommodate smaller bolts or nuts by inserting therein auxiliary rectangular frames or plates, as shown at K.

I do not confine myself to the number of notches *g* herein shown in the plate B, as it is evident they may be more or less in number 70 without departing from my invention, and that with a greater number of notches the wrench can be operated in a more restricted space.

I am aware that it is not broadly new to use a rotary wrench-socket held in any desired position by a ratchet and pawl; but 75

What I claim as new is—

In a socket-wrench, the end-bent spring-pawl C, having the nose *n*, and the handle having recess *h*, in combination with the plate B, 80 having peripheral notches *g*, as and for the purpose specified.

LESLIE PARMER HIATT.
